UNITED STATES PATENT OFFICE.

AXEL R. GUSTAFSON, OF CHICAGO, ILLINOIS.

IRONING-MACHINE.

1,389,753.

Specification of Letters Patent.

Patented Sept. 6, 1921.

Application filed July 10, 1920. Serial No. 395,267.

To all whom it may concern:

Be it known that I, AXEL R. GUSTAFSON, a citizen of the United States, residing at Chicago, in the county of Cook and State 5 of Illinois, have invented certain new and useful Improvements in Ironing-Machines, of which the following is a specification.

This invention relates to ironing machines, and has more particular reference to 10 the ironing members themselves and to the mechanism for operating the same.

One of the primary objects of my present invention is to provide an ironing machine which shall comprise the usual padded roll 15 adapted to coöperate with the heated member, and in addition thereto, an auxiliary padded roll and an auxiliary heated member adapted to coöperate therewith, said auxiliary roll and member being disposed 20 outside the frame of the machine and supported at one end only so as to leave their outer ends exposed, or free to receive articles to be ironed, this auxiliary roll and heated member being particularly adapted 25 for ironing cuffs, collar bands, and the like, which cannot be ironed flat with the main closed end rolls.

Another object of the invention is to provide means for normally urging the padded roll away from the heated roll, and in conjunction therewith, a device for limiting the separating movements between the padded and heated rolls, so that sufficient space is left between the rolls to permit the introduction and withdrawal of articles to be ironed, while at the same time, the rolls are maintained in driving relation by keeping the gears of the respective rolls in mesh.

Still another object of the invention is to 40 provide improved means for moving the padded roll into operative position and to so construct and position this means that it can be readily operated by the foot of the user of the machine either from in front of the machine or from the end of the machine when the auxiliary roll is being used.

Other objects and many of the attendant 50 advantages of this invention should be readily appreciated as the same becomes better understood, by reference to the following description, when considered in connection with the accompanying drawings.

Referring to the drawings:

Figure 1 is a front view partially in sec-

tion of an ironing machine embodying my 55 invention;

Fig. 2 is an end view looking at the left hand end of the machine shown in Fig. 1;

Fig. 3 is a similar view of the opposite end of the machine; and

Fig. 4 is a fragmentary view showing a modified form of heated member.

By reference to the drawings, it will be observed that the machine comprises essentially, a main frame consisting of the upright end pieces 5 and 6, terminating in upwardly and forwardly projecting portions 7 and 8 respectively, the end members of the frame being connected by a plurality of tie bolts 9, each surrounded by a spacing tube 10 or pipe 11, whereby the frame ends are maintained in predetermined spaced relation and rigidly connected together. The forward ends of the upright portions 7 and 8 are similarly connected by a tie rod 12, 15 surrounded by a spacing tube 13, this tube serving not only as a means of connection between the frame members, but also as a guard above the padded roll to prevent the fingers of the operator from being caught 20 between the rolls of the machine.

Between the upper portions 7 and 8 of the frame are journaled the heated rolls 14 and 15 of the ironer, these rolls being heated by any suitable heating means, such for instance, as a perforated pipe 16 (Fig. 1) adapted to be connected to a gas supply. The roll 14 may be similarly heated, the heating means, however, for this roll not being shown. The roll 15 is provided at one end of the 25 machine with a gear wheel 17, and the roll 14 is equipped with a similar gear 18 meshing with and driven by an idler 19 driven in turn by a worm 21 mounted on a shaft 22, which is provided with a pulley 23 over 30 which a belt 24 also engaging with a pulley 25 on the shaft of a motor 26, is trained. A second gear wheel is mounted on the shaft 35 of the roller 14 in position to mesh with the gear 27 on the shaft 28 of the padded roll 30, this gear lying directly back of the gear 27 in Fig. 1 and back of the gear 18 in Fig. 3. The gear 27 is adapted to be moved into and out of meshing relation with the gears 17 and 18 so that rotation of the padded roll 40 29 and the heated roll 15 is effected from the continuously driven roll 14.

The shaft 28 is mounted between the up-

per ends of levers 31 and 32 fulcrumed at 33 and 34 respectively on the end members of the machine frame. Rigidly connected with these levers are forwardly extending arms 34 upon which a table or shelf 35 is mounted at the front of the roll 29. These levers are normally urged forwardly into the position shown in Fig. 3 by expansion springs 36 interposed between the frame and 5 the levers, as shown, so that the gears on the rolls 14, 15 and 29 will normally be out of mesh. In order, however, to maintain the meshing relation between these gears and at the same time permit a limited separation 10 of the rolls to enable the insertion and withdrawal of work, I have provided a device consisting of a hooked link 36' pivoted on the shaft 28 at one end of the roll 29 and adapted to engage over a stud 37 projecting laterally from the machine frame. When this hook is engaged with the stud, the parts will be in the position shown in Fig. 2, the gears of the rolls being still in mesh but the rolls being slightly separated for the purpose explained. 15

The levers 31 and 32 are swung to press the roll 29 against the rolls 14 and 15, and against the force of the springs 36 by foot-actuated means consisting of a pair of levers 38 and 39 fulcrumed on depending projections from the main frame at 41 and 42 respectively, their forward ends being connected by a rod 43 and roller 44 disposed in position to be depressed by the foot of 20 an operator standing in front of the machine. The rear ends of these levers are pivotally connected to the levers 31 and 32 respectively so that upon depression of the foot bar 44, the lower ends of the levers 40 will be swung forwardly and their upper ends rearwardly, to press the padded roll 29 against the heated rolls 14 and 15. Upon release of pressure upon the bar 44, the springs 36 will retract the padded roll to 45 the position shown in Fig. 2 if the hook 36' is in operative position, or to the position shown in Fig. 3 if this hook member be disengaged from the stud 37.

Since the rolls thus far described are 50 mounted between the end members of the frame, both ends are closed. In order to provide for the ironing of collar bands, cuffs and the like, which cannot be ironed flat between these main rolls, I have provided 55 auxiliary means at the side of the frame adapted to accommodate such articles. Referring now to Figs. 1 and 2, it will be observed that upon the projecting end of the journal 45 which carries one end of the roll 15, I have mounted an open ended roll 46 supported at its inner end only outside the frame. This roll is heated by a perforated gas supply pipe 47, which it will be observed, is not connected with the pipe 16 but 60 receives its supply of gas through an inde-

pendent supply cock 48, to which a gas hose may be attached so that roll 46 may be heated simultaneously with or independently of the roll 15.

Likewise, upon the projecting end of the 70 shaft 28, I have mounted an open ended padded roll 49 adapted to coöperate with the roll 46 for ironing purposes, the roll 49 being moved toward or from the roll 46 by the same mechanism and in the same manner as 75 the roll 29 is moved toward and from the main heated member 15.

In using the auxiliary ironing apparatus, the operator will naturally stand at the end of the machine rather than in front thereof, 80 and in order that she may manipulate the padded roll with her foot, the rod 43 is extended outside the frame, where it is equipped with a pedal 51 positioned for actuation by the foot of the operator when 85 the auxiliary ironing apparatus is being used.

While I have shown the heated members in the form of heated rolls, it should be understood that my invention contemplates other forms of heated members, such, for 90 instance, as a shoe 52, shown in Fig. 4. This is an auxiliary shoe corresponding in position and function to the auxiliary heated roll 46, and is heated by an auxiliary gas pipe 53, but such a shoe may be employed 95 in lieu of the main heated roll 15 if desired, without departing from the scope of my invention.

It is believed that my invention, its construction, mode of operation, and many of 100 its inherent advantages will be understood from the foregoing without further description, and while I have shown and described preferred embodiments thereof, it should be manifest that the details of construction are 105 capable of wide variation without departing from the essence of my invention, as defined in the following claims.

I claim:

1. In an ironing machine, the combination 110 of a frame, a heated roll mounted thereon, a padded roll movable toward and from said heated roll, gear wheels on said heated and padded rolls respectively adapted to mesh whereby one roll is driven from the other, 115 means for varying the distance between said rolls, and means for limiting the separating movements of said rolls, so as to maintain a meshing relation between said gears said means being releasable to permit complete 120 disengagement of said rolls and gears.

2. In an ironing machine, the combination 125 of a frame, a heated roll rotatably mounted thereon, a gear wheel affixed to said roll, a padded roll movable toward and from said heated roll, a gear wheel affixed to said padded roll and adapted to mesh with said first mentioned gear, means for urging said rolls apart, means for limiting the separating movement of said rolls so as to maintain 130

- a meshing relation between said gears, said last mentioned means being detachable to permit further separation of the rolls, and foot-actuated means for moving said rolls 5 together.
3. In an ironing machine, the combination of a frame, a heated roll rotatably mounted therein, a gear wheel fixed to said roll, a padded roll movable toward and from said 10 heated roll, a gear wheel fixed to said padded roll and adapted to mesh with said first-mentioned gear wheel, and means for restricting the separating movements of said rolls so as to permit a limited separation 15 but still maintain the driving relation between said gears, said means being releasable to permit further separation of the rolls and disengagement of said gear wheels.
4. In an ironing machine, the combination 20 of a stationary frame, a main heated member mounted within said frame, an auxiliary heated member rigidly connected to said main heated member and supported at one end only outside said frame, a pair of levers 25 fulcrumed on said frame, a main padded
- roll carried by said levers within the frame, an auxiliary roll rigidly attached to said main padded roll and supported at one end only outside said frame in coöperative relation to said auxiliary heated member, a 30 single power means for rotating the main heated member and its auxiliary heated member, and the main padded roll and its auxiliary roll, and means for actuating said levers to move said main and auxiliary rolls 35 as a unit toward and from their respective heated members.
5. In an ironing machine, the combination of a frame, a heated roll mounted thereon, a padded roll movable toward and from said 40 heated roll, driving means interposed between said rolls whereby when one roll is driven the other is rotated, means for permitting one of said rolls to have a movement relative to the other while said rolls 45 are in driving relation, said means being releasable to permit a complete disengagement of said rolls, and driving devices therefor.

AXEL R. GUSTAFSON.
